CORNER LOCKING CONSTRUCTION FOR
PAPERBOARD CONTAINERS

Ralph E. Acker, Fort Worth, Tex., assignor to
Container Corporation of America, Chicago, Ill.,
a corporation of Delaware.

Original application November 29, 1947, Serial No.
788,789. Divided and this application January
6, 1950, Serial No. 137,190.

10 Claims. (Cl. 229—35)

1

This invention relates to a paperboard container of the tray type adapted to be readily erected from a blank and provided with corner locking means which lock the walls in container forming relation upon positioning of the walls in erected condition. More particularly, the invention relates to a corner locking construction for a paperboard container automatically effective upon setting up of the container.

Briefly and generally stated, the invention is embodied in a container having locking tabs on opposite ends of each of one pair of wall members, and slits between adjacent wall members in which the tabs lockingly engage to retain the several wall members in desired trihedral relation to form the corners of the container. The principle of the invention is applicable to many types of containers with wall members in various relations to each other.

It is an object of the invention to provide a paperboard container in which the ends of adjacent wall elements are locked in set up position by cooperating locking means operable simply by movement of the wall elements into position. It is another object to provide a corner locking construction for a paperboard container which is effective automatically upon movement of the container wall members to erected position to lock said members in the erected position. It is also an object to provide a corner lock construction for a paperboard container which will automatically lock the wall members of the container in desired trihedral relation. A further object is to provide a corner lock arrangement for rectangular containers which will retain the walls in desired squared relation. Still another object is the provision of a container in which adjacent wall elements are provided with cooperable locking means at their contiguous portions in such relation that they coact to lock the wall elements in predetermined erected position automatically upon movement of the wall elements to said position. A still further object of the invention is to provide a blank which may readily be folded to form a container with such corner locking construction.

Other and further objects and features of the invention will be apparent to those skilled in the art from the following description and the appended drawings, which form a part thereof.

Fig. 1 is a plan of a blank for an embodiment of my invention; and

Fig. 2 is a perspective view of one end of a container formed from the blank shown in Fig. 1.

2

Referring to Figs. 1 and 2, the invention is illustrated as embodied in a tray suitable for packaging tomatoes and other products. The blank 50 as shown in Fig. 1 comprises a suitable sheet with longitudinal parallel score lines 51 and transverse parallel score lines 52 defining a substantially rectangular bottom panel 53. Side wall panels 54 and end wall panels 55 are connected to the bottom panel along the lines 51 and 52, respectively. End cover flaps 56 are hingedly connected to the end wall panels 55 along hinge lines 57, although these cover flaps may be omitted if desired. Locking tabs 58 are hinged on the end edges of the end wall panels 55 along lines 59. These hinge lines 59 extend at substantially right angles to the lines 52, and are offset inwardly relative to the lines 51 a distance substantially equal to twice the thickness of the material employed for the blank. The tab 58 is divided from the side wall panel 54 by a cut 60, substantially aligned with the line 52. The ends of this cut preferably are curved to extend inwardly relative to the line 52 a distance substantially equal to one thickness of the material. A cut 61, preferably aligned with the line 51, extends from the margin of the blank to the outer end of the tab 58, and a notching cut 62 extends from the inner end of the cut 61 to the outer end of the hinge line 59. This cut 62 serves to provide a notch in the tab when the blank is folded on the line 59.

An end flap 63 is hinged to a portion of the adjacent end edge of the side wall panel 54 along a line 64, a portion of the edge of the flap 63 in alignment with the line 64 being separated from an adjacent portion of the panel 54 by a slit 65. The slit 65 extends outwardly from the outer end of the cut 60 to the inner end of the hinge line 64, and both the slit 65 and line 64 are offset inwardly of the line 52 a distance corresponding to the thickness of the material. The oblique line of cut at the outer end portion of cut 60, which merges into the cut 65, forms a slanting edge portion on flap 63 that provides a flared opening leading to the slit 65 and is adapted to receive the advancing edge of tab 58 and facilitate its subsequent entrance into the slit 65 when the flap 63 is disposed at an angle to its attached wall 54.

The cut 60, being aligned with the line 52 and offset from the slit 65 and hinge line 64, forms an end edge portion on the side wall 54 which extends outwardly beyond the hinge line 64. Thus, when the flap 63 is swung on its hinge line 64 to assume a position substantially at a right

angle to the side wall 54, the projecting portion of the end of the side wall defined by the cut 60 forms a part that may be employed to guide tab 58 prior to its reception into the slit 65.

When the flap 63 is substantially at a right angle to the side wall 54 the slanting edge portion of flap 63, formed by the oblique line of cut 60 where it merges into slit 65, provides one of the sides of the flared opening, the other side of such opening being provided by the end of the side wall 54. The cut 61 separates the flap 63 from the end wall panel 55, and a cut 66 extends from the junction of the cuts 61 and 62 to the cut 60 to separate the flap 63 from the tab 58. The cut 66 is arcuate, but may be straight or otherwise curved, if desired. The dimension of the tab 58 along the cut 60 is smaller than the perpendicular distance from the line 52 to the end of the tab defined by the junction of the lines 62 and 66, and the closed outer end of the slit 65 is at a point spaced perpendicularly from the hinge line 59 a distance no greater, and preferably less, than the distance from the line 52 to the tab end defined by the lines 62 and 66.

A slit 67 is provided in each end wall panel 55 along a line corresponding to the upper edges of the pair of flaps 63 at each end when the blank is erected in container form. As illustrated, this slit 67 is in the shape of a shallow V, since the flaps are shown as so cut that when erected their upper edges will incline downwardly and inwardly from the side walls.

One end of the container formed from the blank of Fig. 1 is shown in Fig. 2. The container may be easily set up by folding the various elements shown and described. The flaps 63 may first be bent upwardly perpendicular to the side panels 54, along the hinge connections described, and the side panels 54 are then bent upwardly along the lines 51 into perpendicular relation to the bottom panel 53, as shown in Fig. 2. As will be clear from the drawing, this positioning of the side panels 54 brings the end flaps 63 into position between the panels 54 at each end in a plane substantially parallel to the plane of the end wall panel 65 when the latter is moved to set up position.

The tabs 58 are then bent along their hinge lines 59 into substantially perpendicular relation with the end wall panels 55, and the panels 55 swung upwardly on the lines 52, with the tabs 58 engaging the inner surfaces of the side wall panels 54. The described offsetting of the hinge lines 59 facilitates this positioning of the tabs relative to the side wall panels, as well as their subsequent movement to locking position.

As movement of the panels 55 to the perpendicular position continues, the tabs 58 engage in the slits 65, and due to the greater dimension of the tabs along its hinge line and the formation of the slit 65 so that its closed end is substantially the same distance from the adjacent corner of the bottom panel 53 as the notching cut 62, the engagement of the tab increases until locking action occurs when the panel 55 reaches its position perpendicular to the bottom panel 53. A rearwardly directed edge or shoulder 68 is provided in each tab 58 by the cut 62 upon folding of the tab on the line 59, this shoulder engaging with the inner end of the hinge line 64, and the adjacent end portion of the tab engaging in the slit 65. The upper edge of the slit 67 provides a shallow tongue which is deflected inwardly of the container for frictionally engaging the upper edges of the end flaps 63, thus providing addi-

tional means for maintaining the flaps in their abutting relation. Instead of the slit 67 being located in the end wall to engage the upper edges of the flaps 63, it could be provided in the form of an inverted V at the bottom of the end wall centrally of the lower edge thereof so that portions of the edges of the flaps 63 would extend into the slit to be frictionally retained in position thereby. After the container has been erected as shown in Fig. 2, it may be filled with tomatoes or other articles and the flap 56 bent inwardly on the line 57 to a substantially horizontal position. A sheet of transparent material may then be used to cover the top of the container. Of course, other covering means may be employed, or no cover provided, as desired.

When the container is set up, the offsetting of the hinge lines 64 of the end flaps inwardly relative to the cut 60 by one thickness of the material permits the end flaps 63 to lie against the inner surface of the end walls 55 without bending or distortion thereof, and positions the edge portion of the side wall 54 defined by the cut 60 in the plane of the outer surface of the end wall 55. A similar result would be achieved as to the locking tabs 58 by offsetting the tab hinge lines 59 a distance equal to one thickness of the paperboard inwardly of the cut 61 and lines 51. For greater ease of insertion of the tabs into the interior of the container and into engagement with the slits 65, however, these hinge lines 59 are preferably offset by twice the thickness of the material. This also allows for spreading of the material at the trihedral corners of the container resulting from bending of the adjacent members. Although the double thickness offset theoretically prevents an absolutely square corner, as a practical matter a square corner is provided because, while the upper portion of the end of the side wall may be held somewhat inwardly of the bottom portion, the bottom portion is in the vertical line of the edge portion of the end wall defined by the cut 61.

This application is a division of my application Serial Number 788,789, filed November 29, 1947, now Patent No. 2,573,379, granted October 30, 1951.

Although the container is shown as provided with a notch in the locking tab for maintaining the tab in locked relation with the other parts of the container, under some conditions and for certain purposes other means may be employed for maintaining the tab in locking relation with the associated slit. For example, the frictional engagement between the tab and the edge portions defining the slit may be used to hold the tab in position, particularly where the container is to be overwrapped with cellophane or the like. In such case, the overwrapping material, once it is applied, serves as a means for maintaining the tab in position. Again, if the paperboard material is relatively compressible, as in the case of corrugated board, retention of the tab in the slit may be achieved solely by its frictional engagement therein. If the slit is so utilized to hold the tab by friction alone, the slit performs a double function in holding both wall members against moving out of their erected positions.

The lock tab may be formed much smaller than as shown, if desired, so as to extend from only an intermediate portion of the edge of the element to which it is hinged. The construction illustrated, however, provides a stronger corner for the container and is, therefore, preferred.

Although the terms "side wall" and "end wall"

have been used in describing the embodiment of the invention, it will be clear that although the container is illustrated as having a rectangular bottom, and the walls as being disposed perpendicular to this bottom, the invention is applicable to other shapes of containers. For example, a six-sided container might be provided employing the corner lock construction of this invention, and similarly, a container employing this lock construction might be provided with the side walls at an angle to the bottom other than a right angle. Such adaptations of the invention to containers of various shapes will be obvious to those skilled in the art, and are clearly within the purview of this invention.

It will be obvious that various changes and modifications in the structure illustrated and described may be made without departing from the principles of the invention. Some of these possible changes and modifications have been pointed out in the foregoing description, and others will readily suggest themselves to those skilled in the art. In view of the variations which may be made in the structure employed to embody the invention, it is not intended to limit the invention to the specific embodiment illustrated and described, but only as required by the spirit and scope of the appended claims.

I claim:

1. A blank for a paperboard container comprising a paperboard sheet cut and scored to provide a rectangular bottom panel, an end wall panel hingedly connected to an edge of the bottom panel, a tab hingedly connected to the end wall panel, a side wall panel hingedly connected to an adjacent edge of the bottom panel, a flap hingedly connected to the side wall along a portion of its end edge, a tab receiving cut formed in the blank extending inwardly in substantial alignment with the flap hinge line, such cut merging in a second cut extending obliquely outward of the end edge of the side wall, such second cut merging in a third cut extending inwardly of the blank and offset outwardly with respect to the flap hinge line, to provide an end edge portion of the side wall extending outwardly beyond such flap hinge line whereby to form a tab guiding element to facilitate reception of the tab into the tab receiving cut, and a cut at a part of the tab hinge line remote from the bottom panel, extending inwardly of the end wall, and providing a notch when the tab is folded on its hinge line, the notch being adapted to lockingly engage the flap at the outer end portion of the tab receiving cut when the blank is erected into container form.

2. A blank for a paperboard container comprising a paperboard sheet cut and scored to provide a rectangular bottom panel, an end wall panel hingedly connected to an edge of the bottom panel, a tab hingedly connected to the end wall panel, a side wall panel hingedly connected to an adjacent edge of the bottom panel, a flap hingedly connected to the side wall along a portion of its end edge, a tab receiving cut formed in the blank extending inwardly in substantial alignment with the flap hinge line, such cut merging in a second cut extending a short distance obliquely outward of the end edge of the side wall, a third cut extending inwardly of the blank substantially parallel with the flap hinge line and offset outwardly with respect thereto, to provide an end edge portion of the side wall extending outwardly beyond such flap hinge line whereby to form a tab guiding element to facilitate recep-

tion of the tab into the tab receiving cut, and a cut at a part of the tab hinge line remote from the bottom panel, extending inwardly of the end wall, and providing a notch when the tab is folded on its hinge line, the notch being adapted to lockingly engage the flap at the outer end portion of the tab receiving cut when the blank is erected into container form.

3. A blank for a paperboard container comprising a paperboard sheet cut and scored to provide a rectangular bottom panel, an end wall panel hingedly connected to an edge of the bottom panel, a tab hingedly connected to the end wall panel, a side wall panel hingedly connected to an adjacent edge of the bottom panel, a flap hingedly connected to the side wall along a portion of its end edge, a tab receiving cut formed in the blank extending inwardly in substantial alignment with the flap hinge line, such tab receiving cut merging in a second cut extending obliquely outward of the end edge of the side wall, and defining an edge portion of the flap, such second cut merging with a third cut extending inwardly of the blank and offset outwardly of the flap hinge line, the end edge portion of the side wall adjacent the flap defined by the second and third cuts being formed to extend outwardly beyond such flap hinge line whereby to form a tab guiding element to facilitate reception of the tab into the tab receiving cut, the second, obliquely extending cut forming an edge portion of the flap which provides, when the flap is disposed at an angle to the side wall, a flared opening between the extended side wall end edge portion and the flap edge portion adapted to receive the tab and guide it into the tab receiving cut.

4. A blank for a paperboard container comprising a paperboard sheet cut and scored to provide a rectangular bottom panel, an end wall panel hingedly connected to an edge of the bottom panel, a tab hingedly connected to the end wall panel, a side wall panel hingedly connected to an adjacent edge of the bottom panel, a flap hingedly connected to the side wall along a portion of its end edge, a tab receiving cut formed in the blank extending inwardly in substantial alignment with the flap hinge line, such tab receiving cut merging in a second cut extending obliquely outward of the end edge of the side wall, and defining an edge portion of the flap, a third cut extending inwardly of the blank substantially parallel with the flap hinge line and offset outwardly with respect thereto, to provide an end edge portion of the side wall extending outwardly beyond such flap hinge line whereby to form a tab guiding element to facilitate reception of the tab into the tab receiving cut, the second, obliquely extending cut forming an edge portion of the flap which provides, when the flap is disposed at an angle to the side wall, a flared opening between the extended side wall end edge portion and the flap edge portion adapted to receive the tab and guide it into the tab receiving cut.

5. A blank for a paperboard container comprising a paperboard sheet cut and scored to provide a rectangular bottom panel, an end wall panel hingedly connected to an edge of the bottom panel, a tab hingedly connected to the end wall panel, a side wall panel hingedly connected to an adjacent edge of the bottom panel, a flap hingedly connected to the side wall along a portion of its end edge, a tab receiving cut formed in the blank extending inwardly in substantial alignment with the flap hinge line, such

tab receiving cut merging in a second cut extending obliquely outward of the end edge of the side wall, and defining an edge portion of the flap, a third cut extending inwardly of the blank substantially parallel with the flap hinge line and offset outwardly with respect thereto, to provide an end edge portion of the side wall extending outwardly beyond such flap hinge line whereby to form a tab guiding element to facilitate reception of the tab into the tab receiving cut, the second, obliquely extending cut forming an edge portion of the flap which provides, when the flap is disposed at an angle to the side wall, a flared opening between the extended side wall end edge portion and the flap edge portion adapted to receive the tab and guide it into the tab receiving cut, and a cut at a part of the tab hinge line remote from the bottom panel, extending inwardly of the end wall, and providing a notch when the tab is folded on its hinge line, the notch being adapted to lockingly engage the flap at the outer end portion of the tab receiving cut when the blank is erected into container form.

6. A blank for a paperboard container comprising a paperboard sheet cut and scored to provide a rectangular bottom panel, an end wall panel hingedly connected to an edge of the bottom panel, a tab hingedly connected to the end wall panel, a side wall panel hingedly connected to an adjacent edge of the bottom panel, and a flap hingedly connected to the side wall along a portion of its end edge and extending along but free of an adjacent portion of the end edge of the side wall to define therewith a tab receiving opening, a portion of the end edge of the side wall being extended outwardly beyond the hinge of the flap to assist in guiding the tab into the opening and the tab being formed with a shoulder adjacent its hinge line remote from the bottom panel and adapted to lockingly engage adjacent the outer end of the opening when the blank is erected into container form.

7. A blank for a paperboard container comprising a paperboard sheet cut and scored to provide a rectangular bottom panel, an end wall panel hingedly connected to an edge of the bottom panel, a side wall panel hingedly connected to an adjacent edge of the bottom panel, a tab hingedly connected to an end edge of the end wall panel, a flap hingedly connected to the adjacent end edge of the side wall panel at a portion thereof spaced from the side wall panel hinge line, and a tab-receiving opening provided by a non-rectilinear cut having at least a portion thereof extending outwardly of the flap hinge line between the flap hinge line and the side wall panel hinge line, said cut defining a portion of the side wall panel end edge projecting outwardly of the folded flap to assist in guiding the tab into the opening when the blank is erected into container form.

8. A blank for a paperboard container comprising a paperboard sheet cut and scored to provide a rectangular bottom panel, an end wall panel and a side wall panel hingedly connected to adjacent edges of the bottom panel, a tab hingedly connected to an end edge of the end wall panel, a flap hingedly connected to the ad-

jacent end edge of the side wall panel at a portion thereof spaced from the hinge line of the side wall panel, and a non-rectilinear cut defining a portion of the side wall end edge and having two spaced points in alignment with the flap hinge line and an intermediate point located outwardly of the flap hinge line, said cut extending between the side wall and a portion of the flap, whereby upon folding of the flap in erecting the container a tab-receiving opening is provided between the flap and the side wall and an end edge portion of the side wall extends outwardly of the folded flap to assist in guiding the tab into the housing.

- 15 9. A blank for a paperboard container comprising a paperboard sheet cut and scored to provide a rectangular bottom panel, an end wall panel hingedly connected to an edge of the bottom panel, a side wall panel hingedly connected to an adjacent edge of the bottom panel, a tab hingedly connected to an end edge of the end wall panel, a flap hingedly connected to the adjacent end edge of the side wall panel at a portion thereof spaced from the side wall panel hinge line, a tab-receiving opening provided by a non-rectilinear cut having at least a portion thereof extending outwardly of the flap hinge line between the flap hinge line and the side wall panel hinge line, said cut defining a portion of the side wall panel and edge projecting outwardly of the folded flap to assist in guiding the tab into the opening when the blank is erected into container form, and means for maintaining the tab in the opening to lock the walls together.
- 20 10. A blank for a paperboard container comprising a paperboard sheet cut and scored to provide a rectangular bottom panel, an end wall panel and a side wall panel hingedly connected to adjacent edges of the bottom panel, a tab hingedly connected to an end edge of the end wall panel, a flap hingedly connected to the adjacent end edge of the side wall panel at a portion thereof spaced from the hinge line of the side wall panel, a non-rectilinear cut defining a portion of the side wall end edge and having two spaced points in alignment with the flap hinge line and an intermediate point located outwardly of the flap hinge line, said cut extending between the side wall and a portion of the flap, whereby upon folding of the flap in erecting the container a tab-receiving opening is provided between the flap and the side wall and an end edge portion of the side wall extends outwardly of the folded flap to assist in guiding the tab into the opening, and means for maintaining the tab in the slit to lock the walls together.
